SWITZERLAND

MERCURY VAPOR ANODE

Application filed August 31, 1931, Serial No. 560,476, and in Switzerland June 27, 1930.

This invention relates to anodes for mercury vapor rectifiers. In anodes for rectifiers of high current intensity it is important to transfer the energy communicated to the anode by the arc. The heat of the anode is drawn off by radiation and conduction, radiation acting primarily towards the interior of the container of the rectifier, while conduction nearly always takes place outwards through the bolt. The latter mode of heat transmission heats the entire upper portion of the anode and above all the packing of the anodes. The heating of the anode packing is especially objectionable for the operation of the rectifier.

The principal object of the invention, therefore, is to retain the insulator and packing of such anodes in cool state.

Other objects and advantages will herein-
20 after appear.

In carrying out the invention, the overheating of the anode packing is reduced as much as possible in the following manner. A division is produced of the heat transmitted from the anode outwards into two streams in such manner as to oppose a great resistance to the heat stream coming in contact with the anode packing, the heat being at the same time transmitted well by radiation and con-
25 duction to the air, while for the other stream of heat which does not come in contact with the packing good thermal conductivity is pro-
30 vided, there being at the same time good transmission of heat by radiation and con-
35 duction to the exterior.

The accompanying drawing shows a cross-sectional view of an embodiment of an anode of this invention.

1 is the head of the anode, 2 the anode insu-
40 lator, 3 the wall of the rectifier vessel, 4 the inner packing, 4a the outer packing, the said inner packing being particularly subject to be-
come overheated. 5 is an outer tube of low thermal conductivity situated against the
45 packing 4, and 6 is an inner tube located with-
in and concentrically with the tube 5. The tube 5 is made as thin as possible, and its up-
per ends is in relatively good communication with the outside atmosphere by means of any
50 suitable radiator 8, whereby a great drop of

temperature takes places necessarily along the tube 5, causing the adjacent packing 4 to remain relatively cool. The inner tube 6 consists of a material providing good thermal conductivity and electrical conductivity. On account of the difference of temperatures between the tubes 5, 6 there results an air current, cool air flowing in from above through the outer circular channel between the two tubes, as shown by the arrow, and flowing outwardly and upwardly through the inner tube 6 and through passageways 7 formed in the latter tube. The said resulting air current is especially effective for the cooling of the packing 4, as the latter is swept by the entering cool air, and in the above manner the heat of the insulator 2 and the entire anode is transferred outwardly by the convection of the resulting air current.

Variations may be resorted to within the scope of the invention, and portions of the improvements may be used without others.

Having thus described the invention, I claim:

1. A vapor anode having therefor a cylindrical insulator, a tube of low thermal conductivity located within said insulator, a tube of high thermal conductivity located within said tube, and leaving an air convecting space between the tubes leading to the exterior atmosphere, and said high conductivity tube having its bore leading to the exterior atmosphere and in its wall a passageway joining the inner spaces of both of said tubes.

2. A vapor anode having therefor a cylindrical insulator, a walled structure within said insulator including an internal chamber connecting with the exterior atmosphere and a chamber surrounding said former chamber connecting with the exterior atmosphere, said chambers being in intercommunication, and said structure including material of various thermal conductivities to cause through convection a stream of air to be drawn into said surrounding chamber toward the walls of the insulator and to be expelled through said internal chamber.

Signed at Zurich, Switzerland, June 23d, 1931.

MAX WELLAUER. 100
